UNITED STATES PATENT OFFICE.

EDWARD E. ARNOLD, OF COVENTRY, RHODE ISLAND, ASSIGNOR TO THE NITROGEN CORPORATION, OF PROVIDENCE, RHODE ISLAND, A CORPORATION OF RHODE ISLAND.

APPARATUS FOR REMOVING THE OXYGEN CONTENT FROM ATMOSPHERIC AIR.

Application filed February 18, 1922. Serial No. 537,591.

To all whom it may concern:

Be it known that I, EDWARD E. ARNOLD, a citizen of the United States, residing at Coventry, in the county of Kent and State 5 of Rhode Island, have invented certain new and useful Improvements in Apparatus for Removing the Oxygen Content from Atmospheric Air, of which the following is a specification.

10 This invention relates to an improved apparatus for removing the oxygen content from atmospheric air, and has for one of its objects the provision of means for igniting a gas mixture of atmospheric air and hydrogen in a suitable casing and supplying heat to the casing during the combustion of said gases whereby combustion of the gases is effected and maintained without interruption so long as the supply of gases thereto 15 is maintained uninterrupted.

Another object of the invention is the provision of means for controlling the supply of gases to the casing in such a manner as to avoid the danger of incomplete combustion of the gases, particularly the oxygen content of the air, by reason of failure of the heating element in the casing to operate properly or the maintenance of the supply 25 of gases in proper proportions.

30 Another object of the invention is to provide means for igniting a gas mixture of atmospheric air and hydrogen in a suitable casing as well as indicating mechanism for warning the operator if for any reason the 35 ignition apparatus fails to function properly.

Other objects and advantages of the invention relates to certain improved details of construction and methods of coordinating 40 the indicating and automatically operating mechanism as will be more fully set forth in the brief description to follow.

In the annexed drawings:

Fig. 1 is a diagrammatic view of one form 45 of ignition and control mechanism which may be employed in carrying out my invention.

Fig. 2 is a diagrammatic view of a modified form of ignition and indicating mech-

anism as applied to a modified form of combustion chamber, and,

Fig. 3 is a diagrammatic view of a further modified form of ignition and indicating mechanism.

In the embodiment of the invention shown 55 in Fig. 1 of the drawings 1 designates an elongated casing which may be formed of ferro-chromium alloy or other suitable heat resistant material and provided adjacent to one end thereof with inlet pipes 2 and 3 for 60 admitting atmospheric air and hydrogen respectively to the interior of the casing. A heating element 4 is positioned within the casing which in the present instance consists of a resistance coil extending through a material portion of the length of said casing 65 and supported therein through plugs 5 and 6 secured after any desired manner in the walls of the casing to prevent leakage of the gases therearound.

70 Valves 7 and 8 are located in the supply pipes 2 and 3 respectively, to which are secured operating arms 9 and 10 for manipulating the valves to open the pipes for the passage of gases therethrough or close the 75 same whenever it may be found desirable. A branch pipe 11 leads from the air pipe 2 adjacent the casing, while a similar pipe 12 leads from the hydrogen supply pipe 3. The pipes 11 and 12 communicate with a cylindrical casing 13 being led therein adjacent to the longitudinal center of said casing while branches 14 and 15 extend from the 80 pipes 11 and 12 respectively and communicate with the interior of the casing 13 85 adjacent the opposite ends thereof. A plunger 16 is slidably mounted within the casing and is provided at one end thereof with an offset contact member 17 for a purpose which will be more fully described herein- 90 after. A pair of spaced pistons 18 and 19 are secured to the plunger 16 within the cylindrical casing 13 for travel within the casing and in contact with the interior surface 95 of the casing wall whereby any predetermined variation of the pressures in the pipes 2 and 3 will result in movement of the plunger 16 and the contact member 17 carried

thereby in one direction or the other through the balanced effect produced by the pressures of the gases between the pistons 18 and 19 within the casing and the unbalanced effect produced by means of varying pressures above the piston 18 and below the piston 19 corresponding with variations of pressure in the pipes 2 and 3.

The resistance element 4 may be heated 10 by an electric current from the main line circuit 20-21 which may be a part of the usual light and power alternating current system. A shunt circuit 23-24 extends from the main circuit and contains a magnet 25, while a second shunt circuit 26-27 extends from the main circuit and contains a similar magnet 28 oppositely positioned relative to the magnet 25 and a normally open switch comprising the contact member 15 29 and the contact points 29 and 30 opposed thereto. A switch 32 is pivotally supported between the adjacent ends of the magnets 25 and 28 and cooperates with contact points 33 and 34 to close a secondary 20 circuit 35 whenever the major portion of the main circuit current is diverted to pass through the magnets 25 or 28. Balanced springs 36 and 37 are secured to opposite sides of the switch 32 and suitably positioned binding posts and normally hold the switch against movement towards either the magnet 25 or the magnet 28 and to return the switch to its normal position upon demagnetization of either of the magnets, the 25 spring 36 being slightly heavier than the spring 37 by reason of the fact that a small amount of current from the main line is normally passing through the circuit 23-24 and the magnet 25.

40 A battery 40 supplies current to the secondary circuit 35 in which are located magnets 41 and 42 and a signal bell or other suitable electric indicating mechanism 43.

The levers 9 and 10 for controlling the valves 7 and 8 are provided with weights 45 and 46 and angular end portions 47 and 48 respectively. A catch 49 pivotally mounted as at 50 normally engages the end 47 of the lever 9 to hold the same against falling under the influence of the weight 45 to close the valve, and a pivotally mounted magnetic switch 51 is connected to the catch 49 by means of the link 52 whereby upon the magnet 41 being energized the catch 49 will be tripped to release the lever 9 and permit the weight 45 to close the valve 7. The lever 10 is similarly supported by a catch 53 pivoted at 54 and connected to a switch 55 by means of link 56 whereby the lever 10 will be similarly released upon the magnet 42 being energized and the valve 8 closed by the weight 46.

When the parts of the apparatus are positioned as shown in the drawings the valves 65 7 and 8 are open to permit air and hydrogen

gas to flow through the pipes 2 and 3 into the casing 1 where the oxygen content of the air and the hydrogen are ignited by the heated resistance element 4 and combine to form water vapor which will pass from the casing 1 through the pipe 60, together with the nitrogen or nitrogen-hydrogen mixture remaining after the elimination of the oxygen content of the air, and into the condenser 61 where any suitable cooling devices 70 are employed to condense out the water vapor from the gas or gases remaining. The proportions of atmospheric air and hydrogen may be suitably regulated by adjusting the valves to permit the gases to enter in 75 such proportions as to form either pure or substantially pure nitrogen upon the removal of the oxygen content from the air or any desired proportion of nitrogen and hydrogen, by admitting hydrogen in the necessary excess of the quantity required to combine with the oxygen content of the air. The current from the main circuit 20-21 being passed through the heating element 4 prior to the introduction of the gases the 80 element 4 is heated to incandescence and serves to ignite the gaseous mixture and maintain the combustion between the oxygen content of the air and the hydrogen by reason of the heat developed in the resistance 85 coil. The constant maintenance of a current through the resistance coil serves to augment the heat generated by the combustion of the gases and insure the complete 90 elimination of the oxygen content of the air with the formation of either substantially pure nitrogen or nitrogen mixed with the desired proportion of hydrogen, the proportions of the mixture remaining constant so long as the flow of the gases continues uninterrupted and the position of the valves 100 remains unchanged. The provision of a thermostat switch 65 in the main circuit causes a break in the circuit whenever the temperature of the resistance element falls 105 below a predetermined point, and any break in or serious injury to the heating coil likewise breaks the main circuit and causes the current to flow through the shunt 23-24 and the magnet 25 thus throwing the switch 110 32 into engagement with the contact 33 to close the secondary circuit 35 and energize the magnets 41 and 42 whereupon the levers 9 and 10 will fall by reason of the weights 115 45 and 46 to close the valves 7 and 8 and thus prevent the possible passage of oxygen from the air into the nitrogen or nitrogen-hydrogen mixture formed as a result of the combustion. At the same time the current from the secondary circuit 35 rings the bell 120 43 to warn the operator that the apparatus has been stopped by the closing of the valves.

The air and hydrogen supplied to the casing 1 from the pipes 2 and 3 are preferably supplied under slight pressure (for example 125

20-30 lbs. per square inch) although suction may be employed to draw the gases into the casing and through the system. In either case the failure for any reason of the normal gas supply in either of the pipes 2 and 3 will result in a variation of pressure which will be instantly communicated to the casing 13 and will cause the plunger 16 to move in one direction or the other to engage the contact 29 or 30. This will immediately close the circuit 26-27 through the magnet 28 and throw the switch 32 into engagement with the contact 34 to close the secondary circuit 35 and stop the flow of the gases to the casing 1 after the manner previously described. Upon the starting of the system the springs 36 and 37 will normally hold the switch 32 in its intermediate position and out of engagement with the contacts 33 and 34 until there occurs some lowering of temperature in the casing 1 below the specified point, a break in the heating coil or a failure in the supply of one of the gases to cause the passage of an excess current through one of the magnets 25, 28.

In the modified form of apparatus shown in Fig. 2 of the drawings, 68 designates an outer tubular casing and 69 an inner tubular casing projecting within the casing 68 and terminating at a point intermediate the ends of the casing 69. The tubular casings 68 and 69 may be made of suitable heat resistant material such as ferro-chromium alloy. An air supply pipe 70 enters the tube 69 adjacent the base thereof and a similar pipe 71 enters the base of the tube 69 to supply hydrogen gas thereto. A hydrogen supply pipe 72 enters the casing 68 adjacent the base thereof to supply an additional quantity of hydrogen thereto in excess of that supplied to the tube 69 through the pipe 71. The pipes 70, 71 and 72 are provided with suitable valves (not shown) for regulating the supply of gases to the tubular casings.

A suitable source of electric current such as a battery 74 is located in a primary circuit 75 which is connected in circuit with a suitable induction coil 76, the secondary circuit 77 of which is grounded as at 78 and connected with a suitable spark plug 79 set into the wall of the casing 68. The spark plug 79 may be so positioned relative to the open end 80 of the tube 69 as to form therewith a spark gap for the discharge of the high tension current from the secondary circuit, or the spark plug may be provided with a grounded terminal for the discharge after the usual manner. A shunt circuit 81 is connected into the battery circuit 75 and is in series with an electric bell 82 and a thermostat 83, the circuit being normally open by reason of the contact 84 being normally out of engagement with the adjustable switch 85 of the thermostat. When the primary circuit 75 is closed a continuous spark is deliv-

ered by the spark plug 79 at the open end 80 of the tube 69, and upon air and hydrogen being admitted through the pipes 70 and 71 the gaseous mixture is ignited and the flame immediately flashes back to a point adjacent the base of the tube 69 where it continues to burn and the heat generated thereby raises the temperature of the interior of the casing 68 to a high temperature. Hydrogen may then be admitted through the pipe 72 and this incoming hydrogen is highly heated by coming in contact with the tube 69 so that as it reaches the end of the tube 69, it is constantly exposed to the spark delivered by the spark plug 79 and will unite with any unburned oxygen coming from the tube 69. Moreover, if for any reason the flame in the tube 69 is extinguished it will be immediately relighted by the sparks from the spark plug 79 on reaching the open end 80 of the tube 69. Any undue fall of temperature in the casing 68 such as may be occasioned by failure of the flame in the tube 69 and the failure of the gaseous mixture to ignite at the open end 80 of the tube 69 will immediately actuate the thermostat switch 85 to engage the contact 84 and close the circuit thus ringing the bell 82 as a warning to the operator that the apparatus requires attention.

It is to be understood that the control mechanism shown in Fig. 1 of the drawings or suitable equivalents thereof may be incorporated in the circuit 81 described above and employed to actuate suitable electrically controlled valves for shutting off the supply of gases to the system immediately upon the lowering of the temperature below a predetermined point and the consequent actuation of the thermostat switch 85.

In the modified form of apparatus shown in Fig. 3 of the drawings the tubular casings 68 and 69 are connected as shown in Fig. 2 with pipes 70, 71 and 72 for supplying air and hydrogen gas to the tube 69 as well as excess hydrogen to the tube 68 after the manner previously described. A battery 90 is connected in a primary circuit 91, the terminals of which are connected with the primary windings of an induction coil 92. One of the terminals of the secondary windings of the coil 92 is grounded as at 93 while the other terminal is connected with a spark plug 94 set in the wall of the tube 68. The spark plug 94 may be so positioned as to form a spark gap with the open end 95 of the tube 69 or the spark plug may be provided with the usual grounded terminal to provide a suitable gap for the discharge of the high tension current from the secondary windings of the induction coil within the tube 68 and adjacent to the open end of the tube 69. A holder 96 is provided adjacent to the spark plug 94 for a "neon tube" 97 of the usual type which serves as a means for indi-

eating to the operator any failure of current in the secondary circuit or defect in the spark plug which interferes with the proper spark-
ing in the tube 68. It will be seen that when

- 5 the current is flowing through the secondary circuit there will be a constant discharge from the spark plug at the open end of the tube 69, and air and hydrogen admitted to the tube 69 through the pipes 70 and 71 will be ignited by the spark discharge and the flame will immediately flash back to the base of the tube 69 where it will burn the oxygen content from the incoming gases with evolution of heat. After the gases are ignited in
10 the tube 69 excess hydrogen may be admitted through the pipe 72 to the tube 68 which will be heated by contact with the tube 69 and as this hydrogen supply reaches the end of the tube 69 it will be caused to ignite with
15 any trace of oxygen which may be previously uncombined in the tube 69 by means of the spark discharge from the spark plug 94. Also if for any reason the flame in the tube 69 is extinguished it will be immediately re-
20 ignited by the spark discharge at the end of the tube 69. While in fact the extinguish-
ment of the flame in the tube 69 will occur only very rarely if ever, the provision of the ignition means shown above serves to pro-
25 vide a safety device for insuring the reignition of the gases so long as the current is properly discharging from the spark plug, and the indicator will immediately disclose the failure of the spark discharge.
30 It is of course to be understood that such changes as will occur to one skilled in the art may be made in the detailed arrangement of the control elements and electrical operating mechanism without departing
35 from the spirit and scope of my invention.

From the above description it will be seen that I have provided a simple and efficient means for maintaining a constant elimination of the oxygen content from atmospheric air to form nitrogen or a nitrogen-hydrogen mixture of high purity and freedom from oxygen such as is necessary, for instance in the manufacture of synthetic ammonia, that means is provided for igniting the gases at all times and constantly maintaining sufficient heat in the ignition chamber to insure complete combustion of the gases as well as to furnish automatic controlling mechanism for positively preventing the continuance of the operation under improper conditions.

Moreover, means are provided for indicating to the operator any failure of the ignition means to operate properly, and if desired there may be coupled with such mechanism suitable means for shutting off the supply of gases to the system automatically upon failure of the ignition means or the lowering of the temperature of the com-

bustion chamber unduly either by reason of 65 extinguishment of the flame or failure of the ignition system to function properly.

What I claim is:—

1. In an apparatus for removing the oxygen content from atmospheric air, a casing 70 of constant capacity, means for conducting atmospheric air and hydrogen into said casing at points located adjacent to each other, a heating element within said casing, and means for maintaining said element in a 75 state of incandescence.

2. In an apparatus for removing the oxygen content from atmospheric air, a casing 80 of constant capacity, means for conducting atmospheric air and hydrogen into said casing at points located adjacent to each other, and means in said casing for constantly maintaining a temperature sufficient to effect the combination of the oxygen content 85 of said air with hydrogen.

3. In an apparatus for removing the oxygen content from atmospheric air, a casing 90 of constant capacity, means for conducting atmospheric air and hydrogen into said casing, means for igniting the gases in said 95 casing, and means for shutting off the flow of said gases to said casing upon the failure of said ignition means.

4. In an apparatus for removing the oxygen content from atmospheric air, a casing, means for conducting atmospheric air and hydrogen into said casing, means in said casing for constantly maintaining a temperature sufficient to effect the combination of the oxygen content of the air with hydrogen, and means for shutting off the flow of the gases to said casing when the quantity of hydrogen supplied is insufficient to combine with the entire oxygen content of the air. 100

5. In an apparatus for removing the oxygen content from atmospheric air, a casing, means for conducting atmospheric air and hydrogen into said casing, means in said casing for constantly maintaining a temperature sufficient to effect the combination of the oxygen content of the air with hydrogen and means for shutting off the supply of said gases to the casing when the temperature within the casing falls below a predetermined point. 105

6. In an apparatus for removing the oxygen content of atmospheric air, a casing of constant capacity, means for conducting atmospheric air and hydrogen into said casing and bringing said gases into contact with each other while relatively undiffused, a heating element in said casing, and means for maintaining the temperature of said heating element sufficiently high to effect the combination of the oxygen content of 110 the air with the hydrogen. 120

7. In an apparatus for combining hydrogen with the oxygen content of atmospheric

- air, a casing of constant capacity, means for conducting atmospheric air and hydrogen into said casing at points adjacent to each other whereby the said gases are brought into contact with each other while relatively undiffused, and means independent of the heat generated by the combination of hydrogen with the oxygen content of the air for constantly supplying heat to the interior of said casing.
8. In an apparatus for combining hydrogen with the oxygen content of atmospheric air to form water, a casing, means for conducting atmospheric air and hydrogen into said casing under pressure, means for igniting the gaseous mixture in said casing and means for shutting off the supply of said gases to the casing when the pressure at which one of the gases is supplied falls below a predetermined point.
9. In an apparatus for combining hydrogen with the oxygen content of atmospheric air to form water, a casing, means for conducting atmospheric air and hydrogen into said casing under pressure, means for igniting the gaseous mixture in said casing, and means for shutting off the supply of said gases to the casing when variation in the pressures at which the different gases are supplied to the casing exceeds a predetermined amount.
10. In an apparatus for combining hydrogen with the oxygen content of atmospheric air to form water, a casing, means for conducting atmospheric air and hydrogen into said casing, means within the casing for igniting the gaseous mixture, and means for shutting off the supply of said gases to the casing upon the supply of either of said gases to the casing falling below a predetermined point.
11. In an apparatus for removing the oxygen content from atmospheric air, a casing, means for conducting atmospheric air and hydrogen into said casing, means for igniting the gases in the casing, means for shutting off the flow of said gases to the casing upon the failure of said ignition means, and means for indicating the shutting off of said gases.
12. In an apparatus for combining the oxygen content of atmospheric air with hydrogen to form water, a casing, means for conducting atmospheric air and hydrogen into said casing, means in said casing for maintaining a temperature sufficient to effect the combination of the oxygen content of the air with hydrogen, means for shutting off the flow of the gases to said casing when the quantity of hydrogen supplied to the casing is insufficient to combine with the entire oxygen content of the air, and means for indicating the shutting off of said gases.
13. In an apparatus for combining the oxygen content of atmospheric air with hydrogen to form water, a casing, means for conducting atmospheric air and hydrogen into said casing for combustion therein, and automatic means for positively controlling the supply of said gases to the casing.
14. In an apparatus for removing the oxygen content from atmospheric air, a casing, means for conducting atmospheric air and hydrogen into said casing, means for igniting the gases in said casing, and means positively operable upon the failure of said ignition means for shutting off the supply of gases to said casing.
15. In an apparatus for removing the oxygen content from atmospheric air, a casing, means for conducting air and hydrogen into said casing, means for igniting the gases in said casing, indicating means for indicating to the operator any failure of the ignition means, means for shutting off the supply of gases to said casing, and means operable upon the failure of said ignition means to simultaneously operate said last named means and said indicating means.
16. In an apparatus for removing the oxygen content from atmospheric air, a casing, means for conducting air and hydrogen into said casing, means for shutting off the supply of gases to said casing, indicating means for indicating to the operator the actuation of the last named means, and means operable when the variation in the flow of said gases to said casing exceeds a predetermined amount to simultaneously operate the means for shutting off the supply of gases to the casing and said indicating means.
17. In an apparatus for removing the oxygen content from atmospheric air, a casing, means for conducting atmospheric air and hydrogen into said casing, electrical means for igniting the gases in said casing, and electrically actuated means for shutting off the flow of said gases to said casing upon the failure of said ignition means.
18. In an apparatus for removing the oxygen content from atmospheric air, a casing, means for conducting atmospheric air and hydrogen into said casing, electrical means for igniting the gases in the casing, electrically actuated means for shutting off the flow of said gases to the casing upon the failure of said ignition means, and electrically actuated means for indicating the shutting off of said gases.
19. In an apparatus for removing the oxygen content from atmospheric air, a casing, means for conducting atmospheric air and hydrogen into said casing, electrical means for igniting the gases in said casing comprising a main circuit, a shunt circuit connected with said main circuit, and means

in said shunt circuit for shutting off the flow of said gases to the casing upon failure of said ignition means.

20. In an apparatus for removing the oxygen content from atmospheric air, a casing, means for conducting atmospheric air and hydrogen into said casing, electrical means for igniting the gases in said casing

comprising a main circuit, a shunt circuit connected with said main circuit, and means in said shunt circuit for indicating the failure of said ignition means.

In testimony whereof I have affixed my signature.

EDWARD E. ARNOLD.
